(57) **CLAIM**

The ornamental design for a jar, as shown and described.

DESCRIPTION

FIG. 1 is a perspective view of a jar showing my new design; FIG. 2 is a side view thereof; FIG. 3 is a bottom view thereof; FIG. 4 is a top view thereof; FIG. 5 is another perspective view thereof, shown with the cap in opened condition; and, FIG. 6 is an exploded view thereof.

The broken line portions show unclaimed subject matter only and form no part of the claimed design.
